CLAIM

The ornamental design for an underwater scooter, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a perspective view of an underwater scooter showing my new design.

Fig. 1.2 is another perspective view thereof;

Fig. 1.3 is a front elevation view thereof;

Fig. 1.4 is a back elevation view thereof;

Fig. 1.5 is a top plan view thereof;

Fig. 1.6 is a bottom plan thereof;

Fig. 1.7 is another front elevation view thereof;

Fig. 2.1 is a front elevation view of a portion of the underwater scooter of Fig. 1.1;

Fig. 2.2 is a back elevation view of the portion, according to Fig. 2.1;

Fig. 2.3 is a right side elevation view of the portion, according to Fig. 2.1;

Fig. 2.4 is a left side elevation view of the portion, according to Fig. 2.1;

Fig. 2.5 is a top plan view thereof of the portion, according to Fig. 2.1;

Fig. 2.6 is a bottom plan thereof of the portion, according to Fig. 2.1;

Fig. 2.7 is another front elevation view of the portion, according to Fig. 2.1.

(Continued)

The broken line showings of a person in Fig. 1.7 and Fig. 2.7 are for the purpose of illustrating environmental subject matter and forms no part of the claimed design.
